UNITED STATES PATENT OFFICE.

FRANK VICTOR NEUVILLE, OF NEW YORK, N. Y.

PIANO.

SPECIFICATION forming part of Letters Patent No. 693,885, dated February 25, 1902.

Application filed May 24, 1900. Serial No. 17,792. (No model.)

To all whom it may concern:

Be it known that I, FRANK VICTOR NEUVILLE, a citizen of the United States, and a resident of 805 East One Hundred and Forty-5 seventh street, New York city, county of New York, and State of New York, have invented certain new and useful Improvements in Pianos, of which the following is a specification, reference being had to the accompanying drawings, forming a part thereof, in which similar letters of reference indicate corresponding parts.

This invention relates to improvements in pianos; and the object thereof is to provide 15 a durable and cheaply-constructed instrument of this character which embodies features of utility and general effectiveness.

The invention will be hereinafter fully described, and specifically set forth in the annexed claims.

In the accompanying drawings, forming part of this specification, Figure 1 is a vertical sectional elevation of my improved piano, taken on a line xx of Fig. 2; Fig. 2, a sectional elevation taken on a line yy of Fig. 1; Fig. 3, a sectional plan view taken on a line zz of Fig. 2. Fig. 4 is a top view of a piano embodying my improved back with the top opened backward.

30 In the practice of my invention I use a string-plate A, which embodies the integrally-formed lower ribbed portion A' and the solid wrest-plank A². This plate is composed of aluminium, and its lower ribbed and open-work part A' may be made in any suitable adapted design, having apertures through which the bridges B³, which are secured to the sounding-board B, may pass, the parts all being cast together to form a homogeneous 35 structure. The wrest-plank A² is extended rearwardly of the plate, and angular side flanges A³ are also extended rearwardly and around the sides and bottom of the plate to receive the sounding-board B, whereby a recess 1 is formed between the plate and sounding-board to allow of free movement and escape of the waves of sound in an upward direction. The sounding-board B is secured to the flanges A³ of the plate A by means of 40 screws b, and a flexible washer b' is placed around each screw to prevent vibrations of the plate from communicating with the sound-

ing-board. These screws thread into the rearwardly-extended flange B' of the sounding-board B, which extends all around the sounding-board to strengthen the same. 55

As a means for securing the plate A within the piano-casing C lugs c are extended laterally from the sides thereof at suitable intervals, and these lugs are riveted to plates 60 c', which are secured to the end frames C' of the piano-casing by means of screws c². These end frames C' of the piano-casing are of novel construction and embody, respectively, solid wooden uprights C² and cross-beams C³, which are doweled or secured to each other in any suitable manner, whereby a strong structure is provided, and held in place by means of the plate A, which owing to the integral formation of its several parts 70 forms a strong brace. A suitable cross-beam C⁴ is also employed in the construction of the casing and also the usual feet C⁵. The outside of each end frame C' is covered by means of suitably-ornamented panels D, and the front 75 of the casing is covered by the usual open-work wall D' and the bottom wall D².

The back of the piano embodies a single wooden plate E, which engages grooves e in the end frames C', whereby the back can be 80 readily removed to afford facility for getting at the interior middle back of the piano should it become necessary to clean or repair that part of the instrument.

On the top of the piano-casing is a hinged 85 lid F, which is hollow to allow of free passage of the waves of sound over the top of the wrest-plank. This lid has an open-work front wall f to allow the sound-waves to escape in a forward direction.

The lower portion A' of the string-plate A is provided with integrally-formed tail-bridges a and a', and the upper portion is provided with the upper bridges a² and a³ and with the holes a⁴ and a⁵ for receiving keys to string 95 the treble and bass strings, respectively, in the usual and well-known manner.

In the operation and use of my invention, the parts being properly assembled, as illustrated in the drawings, I have a strong structure which is cheaply constructed and durable and the quality of the tone is considerably improved, the structure being such that the waves of sound are not interfered with 100

and the necessity of placing the piano against a wall being obviated. To further facilitate movement of the waves of sound, I cut apertures B^3 through the sounding-board B, which 5 allows the sound-waves to pass forwardly and backwardly into the hollow lid F to escape through the front wall thereof.

Having thus described my invention, what I claim as new, and desire to secure by Letters

• Patent, is—

1. In a piano, the combination, of the integrally-formed wrest-plank and string-plate, having angular flanges A^3 , extending rearwardly therefrom, a sounding-board having 15 apertures B^3 , therethrough, to allow waves of sound to pass around the plate, the board having a flange around the edge of its rear surface and being secured by screws threaded into this flange, and the washers surrounding said screws, to prevent direct contact of the board with the plate; with the end frames C', substantially as shown and described.

2. The combination with the frame of a piano, and the sounding-board and string-plate 25 thereof; of the removable backboard E, adapted to slide in the grooves e and by easy removal, to afford facility for reaching the interior back of the piano, substantially as shown and described.

3. In a piano, the combination and arrange-

ment of the string-plate A, the sounding-board B, the angular flanges A^3 , the screws b, and washers b', by which a recess is formed between the string-plate, and the sounding-board, the sounding-board prevented from 35 coming into contact with the string-plate, and the vibrating area of the sounding-board enlarged, all substantially as and for the purpose set forth.

4. In a piano, the combination, of the integrally-formed aluminium wrest-plank and string-plate, having angular flanges A^3 , extending rearwardly therefrom, a sounding-board having apertures B^3 , therethrough, to allow waves of sound to pass around the plate, 40 the board having a flange around the edge of its rear surface and being secured by screws threaded into this flange, and the washers surrounding said screws, to prevent direct contact of the board with the plate; with the 45 end frames C', substantially as shown and described.

In testimony that I claim the foregoing as my invention I have signed my name, in presence of two witnesses, this 21st day of May, 55 1900.

FRANK VICTOR NEUVILLE.
